ATTORNEY

UNITED STATES PATENT OFFICE.

DELLA F. DAVIS, OF HIBBING, MINNESOTA.

DEVICE FOR COATING THREADS.

1,284,254.

Specification of Letters Patent. Patented Nov. 12, 1918.

Application filed June 8, 1918. Serial No. 238,945.

To all whom it may concern:

Be it known that I, DELLA F. DAVIS, a citizen of the United States, residing at Hibbing, in the county of St. Louis and State of Minnesota, have invented certain new and useful Improvements in Devices for Coating Threads, of which the following is a specification.

Every seamstress and others are well aware of the difficulty experienced when threading a needle and particularly when the eye of the needle is small and the thread is of a size to nearly fill the eye when the needle is threaded. This is due chiefly to the end of the thread fraying or opening, hence the common practice of waxing the end of the thread or applying spittle thereto.

The present invention provides means whereby the end of thread may be coated, thereby overcoming the objectionable practice of moistening or applying spittle to the end of the thread preliminary to rolling the same between the thumb and finger to bring the separated ends into close contact whereby the threading of the needle may be easily effected.

The primary purpose of the invention is the provision of a case which contains moistening means and a substance which may be taken up by the end of the finger and applied to the thread simultaneously with the rolling of the same between the thumb and finger in a manner well understood.

A further purpose of the invention is to have the moistening means and the thread coating substance or material closely related and so disposed as to be accessible at all times, whereby they are conveniently at hand when required.

The invention furthermore aims to provide a novelty of the character aforesaid which may be used for advertising purposes and which is dependable for the purpose intended and which furthermore may be marketed at a nominal cost.

The drawing illustrates a preferred embodiment of the invention, however, it is to be understood that in adapting the same to meet different conditions, various changes in the form, proportion, and minor details of construction may be resorted to without departing from the nature of the invention as claimed hereinafter.

In the drawings:

Figure 1 is a side view of an article of the character and for the purpose herein stated embodying the invention.

Fig. 2 is a section on the line 2—2 of Fig. 1 looking in the direction of the arrows.

Corresponding and like parts are referred to in the following description and indicated in both views of the drawings by like reference characters.

The device comprises essentially a case and a supporting arm. The case embodies spaced walls 1 and 2, and an inclosing wall 3. The case may be of any size or form and constructed of any suitable material and, as illustrated, it is of circular outline. One of the walls as 1 is provided with openings 4 and 5 which are separated by means of a cross piece 6. The openings 4 and 5 are elongated, thereby enabling the tip of the finger to obtain an extended bearing on the laterally inclosed wall within the case by means of a sweeping action.

A pad 7 consisting of felt or other suitable absorbent material occupies one-half of the case. A substance 8 of a plastic nature such as soap fills the remaining half of the case. The absorbent 7 and the plastic substance 8 meet on a medial line which is overlapped by the cross piece 6 as shown most clearly in Fig. 2. The absorbent 7 is saturated with water which moistens the tip of the finger preliminary to passing the same over the substance 8 to receive a portion thereof preliminary to rolling the end of the thread between the thumb and finger to bring the parts together and stiffen the same sufficiently to facilitate the threading of the needle in a manner well understood.

An arm 9 is attached at one end to the case, preferably to the inclosing wall 3, and this arm is resilient and curved and is provided at its free end with an opening 10 to receive a suitable fastening by means of which the device may be attached to a suitable stand, shelf, or other support whereby the article is always accessible and in a position to be obtained when required to perform service.

When it is desired to thread a needle, the end of the thread to be passed through the eye of the needle is treated in the following manner:—The end of the finger is passed

over the exposed side of the moistened pad 7 after which the moistened tip of the finger is passed over the soap or other substance 8 to receive a portion thereof, after which the 5 end of the thread is rolled between the thumb and finger in a manner well understood thereby preparing the thread in a manner to admit of its ready passage through the eye of the needle.

10 The foregoing description and the drawings have reference to what may be considered the preferred or approved form of my invention. It is to be understood that I may make such changes in construction, arrangement, and combination of parts, materials, 15 dimensions, et cetera, as may prove expedient and fall within the scope of the appended claim.

Having thus fully described my invention, what I claim as new and desire to secure by 20 Letters Patent, is:—

A thread coating device comprising a case having elongated openings in a wall thereof and having said openings separated by a cross piece, a moistening pad and a coating 25 substance disposed within the case and accessible through the respective openings thereof, said pad and substance meeting on a line which is covered by the cross piece separating the said openings. 30

In testimony whereof I affix my signature in presence of two witnesses.

DELLA F. DAVIS.
